(57) **CLAIM**

The ornamental design for a pet waste removal apparatus, as shown and described.

DESCRIPTION

FIG. 1 is a front right perspective view of the pet waste removal apparatus embodying the design;

FIG. 2 is a bottom left perspective view of the pet waste removal apparatus of FIG. 1;

FIG. 3 is a left side elevation view of the pet waste removal apparatus of FIG. 1;

FIG. 4 is a right side elevation view of the pet waste removal apparatus of FIG. 1;

FIG. 5 is a front elevation view of the pet waste removal apparatus of FIG. 1;

FIG. 6 is a rear elevation view of the pet waste removal apparatus of FIG. 1; and,

FIG. 7 is a top plan view of the pet waste removal apparatus of FIG. 1.
